UNITED STATES PATENT OFFICE.

ALFRED TROSCH, OF ROCHESTER, NEW YORK, ASSIGNOR TO CONSOLIDATED MACHINE TOOL CORPORATION OF AMERICA, OF ROCHESTER, NEW YORK, A CORPORATION OF DELAWARE.

BENDING MACHINE.

Application filed June 14, 1927. Serial No. 198,702.

This invention relates to a bending machine, and has for its principal object to provide a drive mechanism for rotating the rolls and also for adjusting one of the rolls relative to the other, that is simple, efficient, and compact, taking up a minimum amount of floor space and operating smoothly.

Another object is to provide a compact driving mechanism which gives proper speed reduction between the motor and driven roll and thereby permits use of an electric motor with satisfactory results.

Another object is to arrange compact and efficient speed reducing mechanism between the roll elevating and lowering means and the controlling motor therefor so that an electric motor may be used also for adjusting the bodily movable roll.

A further object is to provide an efficient and simple mechanism whereby either end of the bodily movable roll may be adjusted separately or both ends may be adjusted simultaneously.

Still another object is to provide for simple and efficient lubrication of the speed reducing mechanism units controlling both rotation and relative adjustment of the rolls.

With these and other ends in view, the invention comprises the structure and combination of parts which will appear more clearly from the following description when read in conjunction with the accompanying drawings, the novel features being pointed out in the claims following the specification.

In the drawings:

Figure 1 is a side elevation of a bending machine showing one possible embodiment of my invention;

Figure 2 is a plan view thereof;

Figure 3 is a section through the bending rolls of the machine showing their action in bending a plate into cylindrical form;

Figure 4 is an end view of the machine looking at the right end thereof;

Figure 5 is a sectional view taken approximately on the line 5-5 of Figure 2 and illustrating one possible embodiment of the drive for the adjusting mechanism;

Figure 6 is a sectional view taken approximately on the line 6-6 of Figure 2, at right angles to the plane of Figure 5, and

Figure 7 is a section approximately on the line 7-7 of Figure 1.

The invention may be applied to various types of bending machines, and is here illustrated in conjunction with one conventional type having a bed plate 11 with standards 12 and 13 at the ends thereof. Lower bending rolls 14 and 15 are journaled at their ends in these standards, and at their left hand ends carry drive pinions 16 and 17 respectively. An upper bending roll 18 is placed above the rolls 14 and 15 and is adjustable relative to the lower rolls so as to obtain various curvatures on the plates being bent by the machine.

To this end, the ends of the roll 18 are not journaled directly in the standards 12 and 13 but are mounted in members which are movable vertically relative to the standards. The left hand end of the adjustable roll may be journaled in a block 19 which is attached through a pin 20 to a yoke 21 slidable in vertical guideways in the standard 13 and secured at its lower end to a rod 22 having screw threads 23 thereon. The right hand end of the adjustable roll 18 may be journaled in a block 24 connected through the pin 25 to the yoke 26 which is attached at its lower end to a member 27 slidable vertically in a slot 28 in the standard 12. The lower end of the member 27 is pivoted at 29 to a rod 30, which, like the rod 22, carries screw threads at the bottom thereof. Preferably, the block 24 is cut away above the end of the roll 18, and a tapered block 31 is inserted in the opening. The lower side of the block 31 is provided with a suitable bearing surface for the end of the roll 18, and the upward thrust of the roll, when the machine is in operation, is transmitted through the block 31 to the block 24, and thence to the yoke 26. When desired, the tapered block 31 may be withdrawn, thus loosening the roll 18 from the block 24, so that the block, together with the yoke 26 and the member 27, may be swung away from the end of the roll about the pin 29 as a pivot.

To the left of the bed plate 11 is an extension 32 thereof, to which may be attached a pair of vertical rods 33. A cross-piece 34 connects these rods at the top and through this cross-piece is threaded a screw 35 having a hand-wheel 36 at the top thereof and a bearing block 37 at the bottom. This block 37 is arranged, when the screw 35 is

100

105

screwed downward, to bear upon an extension 38 at the left hand end of the roll 18. Therefore, when the yoke 26 has been moved away from the right hand end of the roll 18, as above described, the screw 35 may be utilized to depress the extension 38 and raise the right hand end of the roll, which then pivots about the pin 20. Such a construction is necessary because it is often desired 10 to bend plates into cylindrical form, as shown in Figure 3, and when the cylinder has been completed there is no way of removing it from the rolls except to raise the end of the roll 18, as above described, and 15 slip the cylinder off the end thereof.

The mechanism heretofore described is a well known type of bending machine and forms no part of the present invention. This invention relates to a driving mechanism for rotating the rolls and the mechanism for adjusting the top roll 18 with 20 respect to the bottom rolls.

The drive mechanisms heretofore used on bending rolls have been costly, complicated, 25 and cumbersome. As is well known in the art, bending rolls must rotate at a comparatively slow speed. Where electric motors have been used for driving them, the speed of the motor has been found much too high 30 for the speed of the roll, and it has therefore been necessary to provide a long series of speed-reducing gears in order to accomplish the transition from the high speed of the motor to the low speed of the roll. These 35 gears have taken up a large amount of space, have been costly to manufacture and to keep in repair, have been difficult to lubricate, and have resulted in much loss of power and lack of smoothness. The present 40 invention overcomes these objections by the use of a simple and effective drive which reduces the high motor speed to the required slow speed without difficulty, which is easy and comparatively inexpensive to manufacture and to keep in repair, which takes up 45 comparatively little room, and gives a generally smoother operation. Furthermore, it is easy to lubricate, and greatly reduces the frictional losses.

The invention may be carried out in a 50 number of ways, and as one possible embodiment, there is shown an electric motor 40, mounted upon the bed plate 32 which is rigidly connected to the bed plate 11. Directly connected to the armature shaft of 55 the motor is a worm 41 which drives a worm wheel 42, the latter being fixed to a jack shaft 43 journaled on a pedestal 44. A pinion 45 near one end of the shaft 43 meshes with both the pinions 16 and 17 on the lower rolls 14 and 15. A housing 46 completely surrounds the worm 41 and worm wheel 42, and is preferably made oil 60 tight. This housing may be kept partially 65 filled with oil so that the worm and worm

wheel run constantly in a bath of oil. The worm and worm wheel may be of any suitable material, although it is preferred to use a vanadium steel worm and a phosphor bronze worm wheel because of the good results obtained therefrom. 70

It will be observed that this construction takes up but little room. At the same time, the use of the worm drive reduces the motor speed to the desired roll speed in a single 75 step, thus eliminating the long trains of speed-reducing gearing heretofore used, and doing away also with the excessive frictional losses inherent in such trains. The drive is easily and thoroughly lubricated, 80 since it may be run in a bath of oil. As it consists of but few parts, it is comparatively easy and cheap to manufacture and to keep in order, and takes up much less space than the drives heretofore commonly used. 85

The improved mechanism for adjusting the top roll 18 will now be described. It is apparent from the mechanism described above that the roll 18 may be adjusted by raising or lowering the rods 22 and 30. As heretofore described, these rods each have screw threads near their bottom ends. A worm wheel 50 is threaded upon each of these rods and is retained against vertical movement by suitable thrust bearings 51 and 52 in the standards 12 and 13. Thus it is seen that rotation of the worm wheels 50 will result in screwing the rods 22 and 30 up or down, effecting adjustment of the top roll 18. 100

In order to produce the desired rotation of the worm wheels 50, there may be provided a motor 53 mounted upon the bed plate of the machine, between the standards 12 and 13, where it will take up but little 105 room and thus not increase the floor space of the machine. Directly connected to the armature shaft of this motor is a worm 54 driving a worm wheel 55 on a shaft 56. This worm and worm wheel may be of any suitable material, such as a vanadium steel worm and a phosphor bronze worm wheel. Preferably, an oil-tight housing 57 surrounds the worm and worm wheel and enables them to be run constantly in a bath 110 of oil. 115

Just outside of the housing 57, both ends of the shaft 56 are provided with clutch jaws 58. In alinement with the shaft 56 are two jack shafts 59 and 60 to which are affixed worms 61 and 62 meshing with the worm wheels 50 above mentioned. Clutch jaws 63 and 64 are slidably mounted on the ends of the jack shafts 59 and 60 adjacent the jaws 58, so that they may cooperate therewith. Movement of these jaws may be controlled by pairs of arms 65 and 66 mounted on shafts 67 and 68 respectively. Each pair of arms has, at its upper end, pins engaging slots 69 formed in the clutch 120 125 130

jaws 63 and 64, so that movement of the arms 65 or 66 will slide the clutch jaws 63 or 64 respectively along their shafts, and will thus connect or disconnect the shafts 59 and 60, and the shaft 56.

The shafts 67 and 68 extend through the bed-plate to the front of the machine, as shown in Figures 1 and 2, and are provided at their forward ends with crank arms 70 and 71, respectively, connected to operating rods 72 and 73. These rods are pivoted to operating levers 74 and 75, which are so placed as to be easily accessible to the operator of the machine. Both the main driving motor 40 and the adjusting motor 53 are preferably of the reversing type, so that they may be operated in either direction.

From the foregoing description it is apparent that the upper roll 18 may be adjusted with great ease. Either end of the roll may be raised or lowered by itself, by clutching in one or the other of the clutches 63 or 64, or both ends may be raised or lowered simultaneously by engaging both 25 clutches at once. Rotation of the motor 53 in one direction will raise the roll, while reverse rotation will obviously result in lowering it. By providing separate driving and adjusting motors, it is possible to 30 adjust the rolls at the same time that a plate is being fed through between them, without in any way interfering with the feeding operation.

While one embodiment of the invention 35 has been disclosed, it is to be understood that the inventive idea may be carried out in a number of ways. Therefore it is not desired to limit this application to the precise details shown, but it is intended to 40 cover all modifications thereof falling within the spirit of the invention or the scope of the appended claims.

I claim:

1. In a bending machine, the combination 45 with a plurality of bending rolls, of a driving motor therefor, said motor having a main driving shaft, a worm in alinement with and operatively connected to said driving shaft, a worm wheel driven by said 50 worm, a shaft on which said worm wheel is mounted, the axis of said shaft being parallel to the axis of one of said bending rolls, a pinion on said shaft, and a pinion on one 55 of said bending rolls, said second pinion meshing with said first pinion.

2. In a bending machine, the combination 60 with a plurality of bending rolls, of an electric driving motor therefor, said motor having an armature shaft perpendicular to the vertical plane of the axis of one of said rolls, a worm connected to and in alinement 65 with said armature shaft, a jack shaft perpendicular to the vertical plane of the axis of said armature shaft and parallel to the bending rolls, a worm wheel on said jack

shaft arranged to be driven by said worm, a pinion on said jack shaft, and a pinion on one of said rolls meshing with the pinion on the jack shaft.

3. In a bending machine, the combination 70 of a plurality of bending rolls, one of said rolls being adjustable with respect to another, separate means for adjusting each end of said adjustable roll, an electric driving motor having an armature shaft arranged transversely of the machine, a worm driven by said motor and with its axis arranged transversely of the machine, a worm wheel driven by said worm and having its axis arranged longitudinally of the machine, and means for operatively connecting 75 said worm wheel to either or both of said separate adjusting means, at will.

4. In a bending machine, the combination 80 of a plurality of bending rolls, one of said rolls being adjustable with respect to another, separate means for adjusting each end of said adjustable roll, each of said 85 separate adjusting means including a threaded rod and a worm wheel mounted upon said rod, a worm for driving each of said worm wheels, a shaft upon which each of said worms is mounted, said shafts being aligned with but separated from each other, a driving motor, a worm driven by said 90 motor, a worm wheel driven by said worm, a shaft on which said worm wheel is mounted, said shaft being between and aligned with said worm shafts, and clutches 95 for connecting either or both of said worm shafts with said worm wheel shaft.

5. In a bending machine, the combination 100 of a plurality of bending rolls, one of said rolls being adjustable with respect to another, separate means for adjusting each 105 end of said adjustable roll, an electric driving motor having an armature shaft arranged transversely of the machine, a worm driven by said motor and with its axis arranged transversely of the machine, a worm 110 wheel driven by said worm and having its axis arranged longitudinally of the machine, an oil-tight housing enclosing said worm and worm wheel, and means for operatively connecting said worm wheel to either 115 or both of said separate adjusting means, at will.

6. In a bending machine, the combination 120 of a plurality of bending rolls, one of said rolls being adjustable with respect to another, separate means for adjusting each end of said adjustable roll, an electric driving motor having an armature shaft arranged transversely of the machine, a vanadium steel worm driven by said motor and with its axis arranged transversely of the machine, a phosphor bronze worm wheel driven by said worm and having its axis arranged longitudinally of the machine, and means for operatively connecting 125 said 130

worm wheel to either or both of said separate adjusting means, at will.

7. In a bending machine, the combination of a plurality of bending rolls, one of said rolls being adjustable with respect to another, a longitudinally movable member connected to each end of said adjustable roll, each of said longitudinally movable members having screw threads, a worm wheel threaded upon each of said members, an electric motor mounted below said rolls and having its armature shaft perpendicular to the vertical plane of the axis of one of said rolls, a worm connected to and in alinement 15 with the armature shaft, a worm wheel driven by said worm, said worm wheel being mounted upon a shaft below and substantially parallel to said rolls, jack shafts at each end of and in alinement with said 20 worm wheel shaft, a worm carried by each jack shaft and operatively engaging one of the worm wheels upon the threaded members, and means for connecting either or both of said jack shafts to said worm wheel shaft, whereby rotation of the motor will operate either or both of the first mentioned 25 worm wheels so as to move either or both of said longitudinally movable members to adjust said adjustable roll.

8. In a bending machine, the combination with a plurality of bending rolls, one of which is adjustable relative to another, of an electric driving motor for said rolls, said motor having an armature shaft perpendicular to the vertical plane of the axis of one of said rolls, a jack shaft substantially parallel to the axis of said rolls, a worm driven by said armature shaft, a worm wheel on said jack shaft driven by said worm, a pinion on said jack shaft, a pinion on one of said rolls meshing with the pinion on the jack shaft, a second electric motor mounted below and between the ends of said rolls, said second motor having an armature shaft 40 perpendicular to the vertical plane of the axis of one of said rolls, a worm driven by the armature shaft of the second motor, a worm wheel shaft substantially parallel to the axis of said rolls, a worm wheel mounted upon said worm wheel shaft and driven by said worm, a jack shaft at each end of and in alinement with said worm wheel shaft, said jack shafts extending from the worm wheel shaft substantially to transverse 45 planes drawn through the ends of the bending rolls, means for operatively connecting either or both of said jack shafts to said worm wheel shaft, and means operated by each jack shaft for adjusting one end of the 50 adjustable roll.

9. In a bending machine, the combination with a pair of bending rolls arranged in the same horizontal plane and a single bending roll located thereabove, pinions carried by

each of said pair of bending rolls, a driving 65 motor, a worm driven by said motor, a worm wheel driven by said worm, a shaft on which the worm wheel is mounted, and a pinion carried by said shaft and engaging both the aforesaid pinions on the said pair of bending 70 rolls.

10. In a bending machine, the combination with a pair of bending rolls arranged in the same horizontal plane and a single bending roll arranged thereabove, pinions 75 carried by each of said pair of bending rolls, an electric driving motor having an armature shaft arranged transversely with relation to said bending rolls, a worm driven thereby, a worm wheel engaged by said 80 worm, a shaft carrying said worm wheel, and a pinion on said shaft engaging and driving both the aforesaid pinions of said pair of bending rolls.

11. In a bending machine, the combination with a pair of bending rolls arranged in the same horizontal plane and a single bending roll arranged thereabove, pinions 85 on each of said pair of bending rolls, a driving motor, a worm driven by said motor, a worm wheel driven by said worm, an oil-tight housing enclosing said worm and worm wheel, a shaft on which the worm wheel is mounted, and a pinion carried by said shaft and engaging each of the pinions on the 90 aforesaid pair of bending rolls.

12. In a bending machine, the combination with a pair of bending rolls arranged in the same horizontal plane and a single bending roll arranged thereabove, a pinion 100 on each of said pair of bending rolls, a driving motor, a vanadium steel worm driven by said motor, a phosphor bronze worm wheel driven by said worm, a shaft on which the worm wheel is mounted, and a pinion on said shaft engaging each of the 105 pinions on said pair of bending rolls.

13. In a bending machine, the combination with a plurality of bending rolls, one of said rolls being adjustable with respect to another, a worm wheel for adjusting each end of said adjustable roll, a worm engaging and driving each of said worm wheels, shafts extending longitudinally of the machine in alinement with each other and carrying said 110 worms which engage the worm wheels, an electric motor having an armature shaft and worm arranged transversely of the machine, a worm wheel driven by said worm and having its axis in line with the axes of 115 said longitudinally arranged worm shafts, and means for operatively connecting said worm wheel with said longitudinally arranged worm shafts.

In witness whereof, I have hereunto 125 signed my name.

ALFRED TROSCH.
